UNITED STATES PATENT OFFICE.

HARRY EBERT, OF FREDERICK, MARYLAND.

POWER PLANT.

Application filed March 31, 1919. Serial No. 286,517.

To all whom it may concern:

Be it known that I, HARRY EBERT, a citizen of the United States, residing at Frederick, in the county of Frederick and the 5 State of Maryland, have invented a new and useful Improvement in Power Plants, of which the following is a specification.

This invention relates to improvements in power plants, and more particularly to that 10 class where the power of a prime mover necessarily operating at high speed, is applied to slow moving mechanism without excessive friction and other losses incurred in transmission.

15 It is often advantageous to employ high speed as the initial source of power, as the prime mover in this case is smaller, lighter in weight and relatively more efficient; but it is a well known fact that in gearing down, 20 or sacrificing speed to gain power through the use of gear wheels, belts and pulleys, etc., there are necessarily great losses due to friction and in overcoming inertia of the moving parts, which increases rapidly as the 25 ratio between the speeds of the driver and driven is increased.

The primary object of this invention is therefore to provide means that will reduce these losses and increase the efficiency of the 30 transmission device by producing the maximum final effort with the minimum expenditure of power.

With this and other objects in view, the invention resides in the application of certain principles and forms of construction 35 involving the principle of the lever, the applications of which are clearly set forth in the accompanying specification and drawing, in which:

40 Figure 1 represents a side elevation of my power plant shown driven by an internal combustion engine.

Figure 2 represents a top plan view of my power plant showing the upper water reservoir.

45 Figure 3 represents a rear elevation of my power plant, showing a section of the lower water reservoir.

Similar symbols of reference refer to similar parts throughout the several views. Referring to the drawings, the numeral 1 indicates a foundation, or base, which may be constructed in any approved manner, containing a lower water reservoir, 2. At the rear end of the base 1, three uprights or 50 standards, 3, 4, and 5, which may be con-

structed of wood, metal, or any suitable material, are located, the uprights, 4 and 5 spanning the lower reservoir. These uprights are provided with journals, 3^a, 4^a, and 5^a, respectively, located near their upper ends, through which a rotatable shaft, 6 60 passes.

Two ratchet wheels, 7 and 8, are mounted on the shaft 6, spaced apart, and located between the uprights, 3 and 4, and two sprocket wheels, 9 and 10, are also mounted on the shaft 6, being located between the uprights, 4 and 5. The ratchet wheels 7 and 8, and the sprocket wheels 9 and 10, are all keyed, or otherwise secured to the shaft 6 so as to 70 rotate with it.

A stationary shaft, 11 passes through openings 3^b and 4^b, located near the upper ends of the uprights, 3 and 4, being firmly secured thereto in any approved manner, and two levers, 12 and 13, the ends of which are provided with eyes through which the shaft 11 passes. The levers 12 and 13 are spaced apart, and free to move on the shaft 11, which acts as a fulcrum. A pawl 12^a is pivotally mounted on the lever 12, so as to engage the ratchet wheel 7, being held in engagement therewith by a flat spring, 12^b as shown. The lever 13 is similarly provided with a pivoted pawl 13^a and spring 13^b in order to engage the ratchet wheel 8 in the 80 same manner.

A second pair of levers, 14 and 15, are journaled on a stationary shaft, 16, which passes between and is supported by the two front uprights, 17 and 18, near their upper 90 ends, the shaft 16 acting as a fulcrum for the two levers. The front, or shortest arms of the two levers, 14 and 15, are provided with a roller, 19 and 20, respectively, mounted at their extreme ends, upon which the ends of 95 the main levers, 12 and 13 rest. Guides, or yokes, 14^a and 15^a, serve to keep the ends of the main levers, 12 and 13, always on the rollers in order to prevent any lateral movement.

The longer arms of the levers, 14 and 15, are each connected with a connecting rod, or pitman, 14^b and 15^b, respectively, and the other ends of the pitman are each pivotally connected or journaled to a separate wrist 105 pin on fly-wheels, 21—21, of a prime mover, 22, represented in the drawings as an internal combustion engine which operates the mechanism.

In the drawings, the device is illustrated 110

as lifting water for any purpose, and to this end, endless sprocket chains, 23 and 24, carrying buckets, 25-25, pass over the sprocket wheels, 9 and 10, and submerged sprocket wheels, 9^a and 10^a, convey water from the lower reservoir, 2 to the upper reservoir, 26. The buckets 25-25, are pivotally connected or mounted on rods, 27-27, connecting the two sprocket chains, 23 and 24, so as to remain in an upright position and filled with water until tripped by a stationary rod, 28 after passing over the sprockets, 9 and 10, and the water discharged into the upper reservoir, 26. A bucket is indicated, partly by dotted lines in Figure 1 as discharging into the upper reservoir.

While the device as illustrated shows a method of raising water from one level to another through the medium of buckets, etc., operated by certain speed reducing mechanism, a pulley or pulleys may be mounted on the shaft 6 in place of the sprocket wheels, 9 and 10, and power delivered from such pulleys by a belt for any purpose. Or, the shaft, 6 may be also the main shaft of any piece of machinery, or coupled to any machine.

In operation, the main levers, 12 and 13, are lifted by power applied alternately to their extreme ends by the short, or effort arms of the secondary levers, 14 and 15, fulcrumed on the shaft 16.

As the long or effort arms of the secondary levers, 14 and 15, are connected to the connecting rods, 14^b and 15^b, journaled to wrist pins on the fly wheels, 21-21, set 180 degrees apart, each revolution of the engine shaft alternately raises and lowers each of the main levers, 12 and 13, fulcrumed at their opposite ends on the shaft 11. As each of the main levers starts to fall, the pawls 12^a and 13^a, engage the ratchet wheels, 7 and 8, rotating the main shaft, 6, adapted to fur-

nish the power required, as the drawings disclose, by lifting water through the medium of buckets and sprocket chains. The power of the engine 22 is absorbed in raising the main levers, 12 and 13, which power is afterward put forth by the levers descending and moving the ratchet wheels, 7 and 8, by the pawls, 12^a and 13^a. The rollers, 19 and 20 tend to eliminate friction where the ends of the secondary levers impinge on the main levers, and roller, or other anti-friction bearings may be used where all levers are fulcrumed, further reducing the friction loss to a minimum.

It is obvious that the design may be changed from what I show in many particulars and still keep within the spirit of the invention, therefore I do not wish to be restricted solely to the structure disclosed by the drawings.

I claim:

1. A power plant comprising a lever, a crank member, a generator driving said crank member, a pitman interconnecting said crank and lever, a second lever resting upon the free end of said first lever, and means mounted upon said second lever for transmitting rotary motion to a member to be driven.

2. A power plant comprising a generator provided with a pair of cranks substantially diametrically opposed, a pair of levers driven by said cranks by intervening pitmen, the levers each having a long and a short arm, the long arm connected to the crank, and a second pair of levers operable by said first levers, the second levers each having a long and a short arm, the long arm of the second levers gravitating against the short arm of the first levers and means connected with said second levers for transmitting rotary motion to another member.

HARRY EBERT.
